UNITED STATES PATENT OFFICE.

WILLIAM R. HARTUNG, OF CONNELL, WASHINGTON.

PROCESS FOR PREVENTING CARBON DEPOSIT IN ENGINE-CYLINDERS.

1,277,578.

Specification of Letters Patent. Patented Sept. 3, 1918.

No Drawing.

Application filed February 18, 1918. Serial No. 217,915.

To all whom it may concern:

Be it known that I, WILLIAM R. HARTUNG, a citizen of the United States, residing at Connell, in the county of Franklin and State 5 of Washington, have invented certain new and useful Improvements in Processes for Preventing Carbon Deposit in Engine-Cylinders, of which the following is a specification.

10 My invention relates to improvements in processes for preventing carbon deposits in engine cylinders, more particularly in the cylinders of the internal combustion engines used on automobiles, trucks, and similar motor vehicles, and it consists in the steps hereinafter set forth.

An object of my invention is to provide a process for preventing carbon deposit which does not necessitate the use of chemical carbon removers or the use of steam, or other means which are ordinarily employed in preventing carbon deposit.

20 A further object of my invention is to provide a process for preventing carbon deposit which not only prevents these deposits but actually adds to the life of the engine.

25 Other objects and advantages will appear in the following specification and the novel features of the invention will be particularly 30 pointed out in the appended claims.

In carrying out my invention I chill the 35 interior of the engine cylinder and the piston head so as to produce a hard glazed surface. The material of the engine cylinder and piston should be of such a nature as to adapt itself to the chilling and the hardening. These parts are carefully machined so as to be made as smooth as possible and then the parts are chilled in any suitable manner, 40 such as by heating them and suddenly cooling them in any suitable cooling solution or

liquid, so as to produce a very smooth and very hard surface wherever the carbon is likely to lodge.

Where the interior of the cylinder and the 45 piston head has been chilled, the carbon is unable to find lodgment. Part of it is consumed and part of it passes out with the exhaust gases. The power of the engine is materially increased and as a consequence, the 50 working of the engine as a whole is rendered more efficient, since not only is greater power obtained from a given quantity of fuel, but the life of the engine is prolonged due to the chilling process which hardens the 55 interior of the cylinder and prevents the wearing away, which might otherwise occur.

I claim:—

1. The herein described process of preventing carbon deposit in the cylinders of an 60 internal combustion engine which consists in chilling the interior walls of said cylinders.

2. The herein described process of preventing carbon deposit in internal combustion engines which consists in chilling the interior walls of the cylinder and the piston head to produce a smooth, glazed surface whereby the carbon is prevented from 65 finding lodgment.

3. The herein described process of preventing carbon deposit in internal combustion engines which consists in chilling the interior walls of the cylinder and the piston head thereby producing a hard, smooth, 70 glazed surface whereby the carbon is prevented from finding lodgment.

WILLIAM R. HARTUNG.

Witnesses:

LOGAN L. LONG,
C. V. RICHMOND.

DISCLAIMER.

1,277,578.—*William R. Hartung*, Connell, Wash. PROCESS FOR PREVENTING CARBON DEPOSIT IN ENGINE-CYLINDERS. Patent dated September 3, 1918. Disclaimer filed December 17, 1918, by the patentee.

Enters this disclaimer—

“To that part of the claim in said specification which is in the following words, to wit:

“and then the parts are chilled in any suitable manner such as by heating them and suddenly cooling them in any suitable cooling solution or liquid.”
